UNITED STATES PATENT OFFICE.

DEZSO FRIED, OF BERKELEY, CALIFORNIA.

DESIGN FOR A MEDALLION OR SIMILAR ARTICLE.

47,154.

Specification for Design.

Patented Mar. 30, 1915.

Application filed January 20, 1915. Serial No. 3,419. Term of patent 3½ years.

To all whom it may concern:

Be it known that I, DEZSO FRIED, a citizen of Austria-Hungary, residing at Berkeley, in the county of Alameda and State of California have invented a new, original, and ornamental Design for a Medallion or Similar Article, of which the following is a specification, reference being had to the accompanying drawing, forming part thereof.

The figure is a plan view of a medallion, showing my new design.

I claim:

The ornamental design for a medallion or similar article, substantially as shown.

DEZSO FRIED.
